UNITED STATES PATENT OFFICE

2,677,068

ARC TUBE MOUNT

Ernest C. Martt, Cleveland, Ohio, assignor to
 General Electric Company, a corporation of
 New York

Application December 29, 1951, Serial No. 264,076

3 Claims. (Cl. 313—25)

1

The present invention relates to high pressure electric discharge lamps having an inner arc tube of vitreous material, an outer vitreous envelope and a mount supporting said tube in said envelope.

In the co-pending application Serial No. 246,231, filed September 12, 1951, of Paul A. Dell, which application is assigned to the assignee of the present application, a lamp of this type is disclosed and claimed wherein the arc tube has at each of its ends an externally extending flat press seal portion and the mount includes two channel shaped metal support members each provided with an opening in the bottom of the channel to receive the outer ends of the said flat portions of the arc tube. Spring fingers are stamped out of the bottom of the channel and engage the said flat end portions of the tube.

As pointed out in the co-pending application, since the metal support members disclosed and claimed therein do not engage the hot tubular wall of the arc tube but rather engage the outer ends of the comparatively cool flat seal portions at the ends of the tube difficulties characteristic of prior lamps having metal supports engaging the hot tubular part of the arc tube are avoided. Such difficulties include electrolysis of the vitreous material of the arc tube, thermal shock to the tube and the conduction of heat from the tube by the supports. The advantages of the novel structure of the lamp of the co-pending application also include a shorter warm-up time, that is, the time required for the lamp to attain its normal high operating vapor pressure after starting of the discharge, and elimination of distortion of the metal supports by the intense heat at the tubular portion of the arc tube.

An object of the present invention is to provide arc tube support members for use in lamps of the above type which are inexpensive to manufacture by mass production methods and which are readily attachable to the mount for the arc tube in the envelope. Another object of the invention is to provide an arc tube mount including such members. Further objects and advantages of the invention will appear from the following detailed description of a species thereof.

In the drawing accompanying and forming part of this specification a species of the invention is shown in which Fig. 1 is a front elevational view of a discharge lamp of the high pressure type in which the support members for the inner arc tube embody the present invention, Fig. 2 is a front elevational view on an enlarged scale of one of said support members and Fig. 3

2

is an auxiliary elevational view of the support member shown in Fig. 2 taken at an angle of 30 degrees as indicated by the arrow.

Referring to Fig. 1 of the drawing the lamp 5 comprises an outer vitreous envelope 1 having a re-entrant stem 2 through the pinched or pressed part 3 of which extend the leading-in wires 4 and 5 which are connected at their outer ends to the contacts on the usual screw type 10 base 6 of the lamp and terminate within the outer envelope for connection to the terminals of the inner arc tube 7.

The inner arc tube 7 is made of hard vitreous material, such as quartz, and has sealed therein 15 at opposite ends thereof a pair of main discharge supporting electrodes 8 and 9 of tungsten and material of higher electron emissivity, such as alkaline earth oxide and/or thorium, the inleads 11 and 12 of which constitute the arc tube terminals. An auxiliary starting electrode 10 is sealed into one end of the tube 7 adjacent the main electrode 8. The current inlead wires 11, 12, and 13 for said electrodes 8, 9 and 10, respectively, have a thin flattened section hermetically 20 united with the pinched tube portions 14 and 15 extending outwardly from the arc tube 7 as described and claimed in the co-pending application of Edward B. Noel and Paul A. Dell, Serial No. 244,818, filed September 1, 1951, titled 25 "Ribbon Lead Construction," and assigned to the assignee of this application. In the 100 watt size the arc tube 7 has a filling of starting gas, such as argon at a pressure of 20 millimeters, and a measured quantity of mercury sufficient to 30 produce a high pressure, unsaturated vapor atmosphere at the operating temperature of the arc tube 7.

The mount for the arc tube 7 within the outer envelope 1 comprises a harness made up of a U-shaped stiff metal wire having its bent center portion 16 welded to the inlead 4 of stem 2 and its parallel legs 17 and 18 extending longitudinally of the arc tube 7 and terminating at the opposite end of the outer envelope 1. A pair of 35 spring members 19 and 20 press against the envelope 1 and are welded to the free ends of the legs 17 and 18. The U-shaped support is thus firmly held in position in the envelope 1.

The arc tube 7 is attached to the U-shaped 40 support by transverse metal support members 21 welded to the legs 17 and 18 of the U-shaped support and engaging the corners of the outer ends of the pinched portions 14 and 15 of the tube 7. The supports 21 at each end of the tube 7 are 45 identical in structure and are constituted by flat

strips of metal, such as nickel plated iron or chrome iron, each having a pair of spaced ears or lugs 22 and 23 punched out of its central portion and bent in a curve to fit and engage the said corners of the pinched parts 14 and 15 of the tube 1.

The support members may be made in a single punching operation from a strip of metal and are thus susceptible of mass production at low cost.

Further, the outer end portions of the members 21 may be attached to both legs 17 and 18 of the U-shaped mount in a single operation by welding while being held in proper position with respect to the said legs by a jig to minimize the cost of assembly.

The curved ears 22 and 23 of the support members 21 are cut and bent in such manner that the end thereof integral with the member 21 is at an angle of about 30° with respect to the longitudinal axis of the strip member 21 and said ears incline toward each other as best shown in Figs. 2 and 3. Thus, when the arc tube 7 is positioned in the amount including a pair of support members 21, relative movement between the said tube 7 and the said mount either longitudinally or laterally of the tube 7 is prevented in a positive manner and the tube 7 is firmly supported by the amount in the envelope 1.

In order to allow for expansion of the vitreous members and the metal members of the lamp at different rates during service I prefer to allow slight play between the corners of the pinched portions 14 and 15 of the tube 7 and the ears 22 and 23 of the supports 21 to prevent fracture of the quartz tube 7 and distortion of the metal supports 21.

Positioning the transverse flat strip support members 21 in a plane parallel to the axis of the tube 7 provides maximum strength for minimum thickness of the strip while providing also the necessary rigidity for supporting the arc tube 7 in a predetermined position within the envelope 1. The thin support members 21 so positioned also offer minimum shadow casting obstruction to the light emitted by the discharge axially of the arc tube 7.

The electrical connections between the electrodes 8, 9 and 10 and the current inleads 4 and 5 are made in the conventional manner. Main electrode 9 is connected through its inlead 12 and the flexible conductor 24 to the leg 17 of the U-shaped mount, the center portion 16 of which is welded to the inner end of current lead 4. The main electrode 8 is connected through its inlead 11 and the flexible conductor 25 to the inner end of inlead 5. The auxiliary electrode 10 is electrically connected to the main electrode 9 through its inlead 13, the flexible conductor 26, the resistor 27 and the stiff wire conductor 28 welded to the leg 17 of the U-shaped mount.

What I claim as new and desire to secure by Letters Patent of the United States is:

1. A mount for a straight vitreous arc tube

having at each end an external flat press seal portion, said mount comprising a pair of spaced parallel substantially rigid metal wires and means to secure said tube longitudinally between said wires, said means consisting of a pair of thin metal flat strips extending transversely of and substantially in the plane including said wires and attached to said wires with their flat sides against said wires, each of said strips having a pair of integral curved ears spaced apart longitudinally thereon, extending generally toward a longitudinal edge thereof and being inclined slightly toward each other, said strips being attached to said wires with their ears directed to the arc tube mounting space between said wires to provide seats for the outer end corners of the flat press portions of the arc tube.

2. A mount for a straight vitreous arc tube having at each end an external flat press seal portion, said mount comprising a pair of spaced parallel substantially rigid metal wires and means to secure said tube longitudinally between said wires, said means consisting of a pair of thin metal flat strips extending transversely of and substantially in the plane including said wires and attached to said wires with their flat sides against said wires, each of said strips having longitudinally spaced portions thereof cut and bent outwardly to form a pair of curved ears extending generally toward a longitudinal edge of the strip and being inclined toward each other, said strips being attached to said wires with their ears directed toward the arc tube mounting space between said wires to provide seats for the outer end corners of the flat press portions of the arc tube.

3. A support member for a vitreous arc tube having flat external press seal portions at its ends, said support member consisting of a thin metal flat strip having longitudinally spaced portions thereof cut and bent outwardly to form curved ears extending generally in the direction of a longitudinal edge of said strip and being inclined toward each other, the ends of said ears being spaced apart from each other and from said strip a sufficient distance to engage the outer corners of the flat press seal portion at one end of said arc tube.
